UNITED STATES PATENT OFFICE

HOWARD F. WEISS, OF MADISON, WISCONSIN, ASSIGNOR TO C. F. BURGESS LABORATORIES, INC., OF MADISON, WISCONSIN, A CORPORATION OF DELAWARE

FACING MEMBRANE FOR SOUND-ABSORBING MATERIALS

Application filed January 21, 1928. Serial No. 248,523.

This invention relates to improvements in facing membranes for sound-absorbing materials, such as are used on walls, ceilings and the like.

5 It is an object of my invention to provide a woven fabric having a pleasing appearance which may be used for a facing membrane for sound-absorbing materials and which may be painted or otherwise decorated without clogging the interstices or apertures, whereby the sound reaches the sound-absorbing material. It is a further object of my invention to provide a fabric membrane which is stiff enough and does not sag perceptibly when used to cover sound-absorbing materials mounted on ceilings. Other objects will become apparent from the specification and drawings wherein;

Fig. 1 shows one type of my improved 20 membrane;

Fig. 2 is a cross-section, somewhat enlarged of the thread used in Fig. 1;

Fig. 3 shows another type of membrane;

Fig. 4 is a cross-section of the pairs of 25 threads used in Fig. 3;

Fig. 5 is a cross-section of the pairs of threads of Fig. 3 when subjected to heavy pressure;

Fig. 6, 7 and 8 illustrate alternative methods of installing the membrane in acoustical treatments.

In the acoustical treatment of walls and ceilings of rooms and auditoriums it is the general practice to mount a sound-absorbing 30 material, such as hairfelt, balsam-wool, and the like on the wall or ceiling and face this treatment with a covering membrane which protects the sound absorber and is capable of being decorated. In the past these membranes have been made of cheesecloth, burlap, and similar woven fabrics. These fabrics give excellent results when first installed. However, they soon become dirty and it is practically impossible to wash them while 35 they are on the wall or ceiling. It may be possible to decorate or redecorate them once or twice if care is used in applying the decorative material, but the fabric soon becomes clogged with the paint or other decorative 40 material and as a result the passage of sound

to the absorber is nearly cut off and the treatment becomes much less efficient. The smallness of the interstices and the fuzzy nature of the fabric both contribute to its rapid clogging.

55 I have discovered that a fabric, woven of materials free from fuzz and woven so that apertures are formed in the finished fabric, is suitable for covering sound-absorbing materials and overcomes the objections to cheesecloth, burlap and the like. A material which is satisfactory and cheap is a fabric woven from paper threads, as such paper threads are practically free from fuzz. Other fuzz-free materials may be used however. A narrow 60 cut paper strip, especially when made of tough stock such as kraft, when twisted forms a tough thread or string 10, having a smooth surface free from fuzz and which has a stiffness which makes it especially suitable 65 for a covering membrane. Such a paper thread may be rolled or pressed into a flat string as shown in cross section in Fig. 2. The paper thread or other fuzz-free material is woven into a fabric having apertures 70 formed therein by the weaving as shown in Fig. 1. This is done by keeping the threads of either or both the warp and woof separated a suitable distance during the weaving. Holes 1/32" square or larger are suitable. Although single threads may compose the warp 75 and woof strands these should be at least from 3/128" to 1/32" in diameter so that the fabric has some body. I prefer to use a much heavier thread which is flattened to the shape shown in Fig. 2. Such a paper thread after flattening may be about 1/64" x 1/16" 80 in cross section. A fabric woven from this flattened thread with apertures at least 1/32" square has a body and stiffness which is desirable as will be explained hereinafter.

85 In another modification as shown in Fig. 3, the separate strands of the warp and woof are composed of two or more parallel threads 90 shown in cross section in Fig. 4 and woven to leave apertures at least 1/32" square. The finished fabric may be passed between squeeze rolls to flatten out the threads to some extent as shown in Fig. 5, thereby giving the 95 fabric a smooth appearance and giving a 100

final result closely resembling that obtained with the single flattened thread. The finished fabric may be used as a membrane for sound-absorbing material as shown in Fig. 6 in which the wall or ceiling 12 has furring strips 13 attached to it. Sound-absorbing material 14, such as hairfelt, balsam-wool, or the like is put in place and the apertured woven fabric 15 is placed over it, being nailed or otherwise fastened to the furring strips 13, as shown at the right hand end of Fig. 6, or by being pinched between spaced furring strips, as shown at the left hand end, or by the various other methods known to those skilled in the art. In another method of installing the treatment, the furring strips may be dispensed with and the material fastened directly to the walls or ceiling.

The apertures in the fabric allow the sound to pass into the sound-absorbing material 14. An acoustical facing membrane made in this manner has a surface which may be painted from time to time without danger of closing the apertures if ordinary care is used and especially if a low viscosity paint is used. The surface, being smooth and free from fuzz, may be washed and cleaned without removing the material from the walls or ceiling.

Since paper is subject to humidity it is desirable to protect it as much as possible. It is also desirable to further stiffen the fabric sufficiently, so that it will not sag between supports, thereby improving its appearance. I accomplish this by dipping the woven fabric into, or otherwise treating it with a colloidal sizing material, such as hide-stock glue, agar-agar, a phenolic condensation product, Duco and the like. These must be of such consistency as not to close the apertures. The sizing coats the threads and in accordance with the characteristic effect of a colloid upon fibrous material, shrinks and stiffens the fabric, thereby preventing sagging and the absorption of moisture. By stiffening the woven fabric in this manner it is possible to preform it into shallow pan-shaped units 16, which may be handled without danger of collapsing, as shown in Fig. 7. Such pans, made of stiffened fabric, may be used with suitable lengths of furring strips, such as shown in Fig. 6 or the frame 17 of Fig. 8.

The glue may be waterproofed by means of dichromate as is well known to those skilled in the art. Colors may also be incorporated in the stiffening substance. It is also possible to coat and stiffen the fabric with metals, as by electroplating as practiced in the galvano-plastic art or by the Schoop process of spraying, whereby a thin adherent metallic coating is formed on textile or paper fabrics without injury to the fabric. The metallic coating has obvious advantages such as added stiffness and fire resistance. Such a

metallized fabric may be readily cleaned as well as a fabric, the threads of which consist of metal strands.

The sound absorbing material in the form of pads, as shown in Fig. 6, may rest within the stiffened fabric pans and be supported thereby, or they may be secured to the ceiling or wall in any convenient manner, as for example by means of glue and in some cases the treated paper fabric may be glued to the sound absorbing pad, water proof glue such as casein glue being used in such cases.

What I claim is:

1. A shallow, pan-shaped facing unit for sound-absorbing material comprising a membrane of fuzz-free paper-thread fabric, said fabric being stiffened sufficiently to retain said pan-shape and woven to leave apertures therein. 80

2. A shallow, pan-like facing unit for sound-absorbing material comprising a membrane of paper-thread fabric, said fabric being stiffened sufficiently to retain said pan-shape by means of a colloid and woven to leave apertures therein. 85

3. A sound-absorbing construction for walls and ceilings comprising sound-absorbing material associated therewith and a decoratable facing membrane substantially concealing said sound absorbing material and consisting of woven threads of non-fuzzy material, partially flattened and spaced apart to leave substantial openings for the penetration of the sound. 95

4. A sound absorbing construction for walls and ceilings comprising sound-absorbing material associated therewith and a decoratable facing membrane consisting of woven strands spaced apart to leave substantial openings for the penetration of sound, said strands each comprising at least two parallel threads of non-fuzzy fibrous material. 100

5. A sound-absorbing construction for ceilings and the like, comprising spacing members of equal thickness secured to said ceiling, sound-absorbing material positioned adjacent said ceiling and a facing membrane for sound-absorbing material consisting of woven threads of smooth material spaced apart to provide interstices and secured to adjacent spacing members to form a panel, said woven threads, of themselves, lacking sufficient stiffness to maintain said panel as a flat surface but stiffened to prevent sagging whereby a series of said panels lie in substantially the same plane. 110

6. A sound-absorbing construction for ceilings and the like, comprising spacing members of equal thickness secured to said ceiling, a facing membrane consisting of woven threads of smooth material spaced apart to provide interstices and secured to adjacent spacing members to form a panel, said woven threads, of themselves, lacking 125

sufficient stiffness to maintain said panel as a flat surface but stiffened to prevent sagging, whereby a series of said panels lie in substantially the same horizontal plane and sound absorbing material supported by said panels.

5 In testimony whereof, I have subscribed my name.

HOWARD F. WEISS.
